(57) **CLAIM**

The new ornamental design for a walking cane, as shown and described.

DESCRIPTION

FIG. 1 is a perspective view of the walking cane showing my new design;

FIG. 2 illustrates a front elevation view of the walking cane of FIG. 1;

FIG. 3 is a left side view of the walking cane;

FIG. 4 is a right side view of the walking cane;

FIG. 5 is a rear elevation view of the walking cane;

FIG. 6 is a top plan view of the walking cane; and,

FIG. 7 is a bottom plan view of the walking cane.

The broken line showing of environment is for illustrative purposes only and forms no part of the claimed design.

1 Claim, 7 Drawing Sheets
